Patented Jan. 8, 1918.

UNITED STATES PATENT OFFICE.

JOHN J. McNICHOLAS, OF PHILADELPHIA, PENNSYLVANIA, ASSIGNOR TO NOTASEME HOSIERY COMPANY, OF PHILADELPHIA, PENNSYLVANIA, A CORPORATION OF PENNSYLVANIA.

PICTURE-FRAME.

1,252,918.

Specification of Letters Patent.

Patented Jan. 8, 1918.

Application filed May 7, 1917. Serial No. 166,931.

To all whom it may concern:

Be it known that I, JOHN J. McNICHOLAS, a citizen of the United States, residing in the city and county of Philadelphia, State of Pennsylvania, have invented a new and useful Picture-Frame, of which the following is a specification.

My invention consists of a novel construction of a picture frame whose front is composed of a continuous sheet of celluloid or similar transparent material having at its outer portion a border or frame or simulation of a frame, which is wholly or partly opaque, whereby a pleasing appearance is imparted to the entire frame, and an advertisement, card, drawing, photograph or the like held therein will have the appearance of a specially framed picture, so that an inexpensive display card will look like an expensive framed picture, the article displayed being kept clean and in good condition at all times.

It further consists of a novel manner of assembling a sheet and the border or frame therefor with respect to the back or body of the same.

It further consists of other novel features of construction, all as will be hereinafter fully set forth.

For the purpose of illustrating my invention, I have shown in the accompanying drawing a form thereof which is at present preferred by me, since the same will be found in practice to give satisfactory and reliable results, although it will be understood that the various instrumentalities of which my invention consists can be variously arranged and organized, and that my invention is not limited to the precise arrangement and organization of these instrumentalities as herein shown and described.

Figure 1 represents a front perspective view of a picture frame embodying my invention.

Fig. 2 represents a rear perspective view of Fig. 1, on a reduced scale.

Fig. 3 represents a section on line 3—3 Fig. 1.

Fig. 4 represents a section on line 4—4

Fig. 1.

Fig. 5 represents a perspective view of the front showing the opaque border employed as a frame in detached position.

Fig. 6 represents a transverse section of another embodiment of my invention.

Similar numerals of reference indicate corresponding parts in the figures.

Referring to the drawings.

1 designates a frame proper and 2 designates a thin plate of sheet metal or similar material having the slot 3 therein for the insertion of an advertising card, drawing, plate, photograph or the like, which is to be displayed and which can be changed as often as desired, the edge or portion 4 of said slot 60 being deflected upon the back 5 of the device to which is attached the rear support or prop 6, said parts 5 and 6 being of paper, cardboard or similar material if desired.

7 designates a transparent sheet of celluloid or similar transparent material having an opaque frame or border 8 secured thereto, the outer terminals of said sheet and border 7 and 8 being coextensive and deflected, as indicated at 9 and 10, the edges of said deflected portions being held between the deflected outer portions 11 and 12 of the metal sheet 2, as will be understood from Figs. 3 and 4, while the outer edge of the sheet 7 and the contiguous opaque frame or border 80 8 is brought over and around the edges of the back 2 of sheet metal or other material so that the entire device has a neat and finished appearance.

The inner contour of the opaque frame or border 8 may be square or polygonal, as indicated at the upper and lower edges 13 and the side edges 14, or it may be oval or other contour. It will be seen that the entire easel front being composed of the celluloid or 85 similar transparent sheet, having the opaque border or frame 8, whose inner edges 13—13 and 14—14 define or constitute the boundaries of the window, will give to an inexpensive display card the appearance of an 90 expensive framed picture and the latter will in addition be always kept clean and in good condition and furthermore the display card, advertisement, photograph or the like will have the appearance of a specially framed 95 picture.

The frame or border 8 which is preferably partly or wholly opaque can be made of material separate from the celluloid placed either inside or outside of the easel, 105 or the frame, configuration, simulation or contour can be printed, pressed, stamped or otherwise directly or indirectly impressed or embossed on the celluloid sheet 7. Any desired design for the frame 8 may, for ex- 110

ample, be lithographed on paper and placed under the celluloid, so as to show therethrough, or the frame design or contour might be lithographed on steel and placed 5 on the front of the celluloid sheet 7.

The easel back or body portion 2 may be made of cardboard or sheet metal and pressed out by suitable dies, punches or similar implements to hold the card inserted in 10 perfect alinement. The celluloid sheet 7 may although it doesn't have to extend across the entire front portion of the frame proper thereby giving a pleasing and ornamental appearance thereto and to the card, advertisement, photograph or the like held at the 15 back thereof, and I preferably give the outer edge of the sheet 7 and the frame coating therewith the appearance of being beveled, as indicated at 15. The picture, display 20 card, advertisement or the like is inserted or withdrawn at the slot 3, as is evident.

In Fig. 6 I show the edge portion of the transparent sheet 7 and similar portions of the back 5 clamped and held together by the 25 marginal rim 9 which extends around the rear portion of the frame of the device and overlaps the side and bottom edge portions of the back leaving the top of the back open, said top and body of said back set out from 30 the edge portions of said sheet so as to form the slot or throat 3 through which the card, picture, etc. may be inserted between the transparent sheet and back and removed therefrom.

35 It will now be apparent that I have devised a novel and useful construction of picture frame which embodies the features of advantage enumerated as desirable in the statement of the invention and the above 40 description, and while I have, in the present

instance, shown and described a preferred embodiment thereof which will be found in practice to give satisfactory and reliable results, it is to be understood that the same is susceptible of modification in various particulars without departing from the spirit or scope of the invention or sacrificing any of its advantages. 45

Having thus described my invention, what I claim as new and desire to secure by Letters Patent, is:—

1. A picture frame having a back with a slot therein, a transparent celluloid sheet extending completely across said back and secured thereto at the rear of said back, and 55 a frame proper carried by or attached to said transparent front.

2. In a picture frame, a back having means for the insertion of the matter to be displayed, a sheet constituting a transparent 60 front extending completely across said back, and a frame adjacent to said front, the outer edges of said front and frame being coextensive and bent around the edges of said back, the latter having at its rear a continuous outwardly deflected lip which retains 65 said front and its frame in assembled position with respect to said back.

3. In a picture frame, a frame proper, a back having means for the insertion of the 70 matter to be displayed, and a sheet of transparent material extending across said back, said frame having at its rear a marginal rim which clamps the edge portions of said back and sheet.

JOHN J. McNICHOLAS.
